HOLDER FOR NAPKINS

Peter Beghetti, San Francisco, Calif.

Application August 23, 1947, Serial No. 141,018

Term of patent 3½ years

(Cl. D44—24)

To all whom it may concern:

Be it known that I, Peter Beghetti, a citizen of the United States, residing at 30 Telegraph Place, San Francisco, State of California, have invented a new, original, and ornamental Design for a Holder for Napkins, of which the following is a specification, reference being had to the accompanying drawing, forming a part thereof.

Fig. 1 is a plan view of a holder for napkins, showing my new design;

Fig. 2 is a front elevational view; and

Fig. 3 is a sectional view thereof through line 3—3 of Fig. 2.

I claim:

The ornamental design for a holder for napkins, as shown.

PETER BEGHELLI.
